PALM SUPPORTED FINGER OPERATED SWITCH

Chester B. Rackson, 22 Orchard Drive,
Woodbury, N.Y. 11797

Filed Mar. 13, 1974, Ser. No. 450,849

Term of patent 14 years

Int. Cl. D13—03

U.S. Cl. D26—13 R

FIG. 1

FIG. 2

FIG. 3

FIG. 4

FIG. 5

FIG. 6

FIG. 7

FIG. 8

FIG. 1 is a perspective view of a palm supported finger operated switch showing my new design;

FIG. 2 is a bottom view;

FIG. 3 is a view of the side opposite that shown in FIG. 1;

FIG. 4 is a front view;

FIG. 5 is a perspective view of another palm supported finger operated switch;

FIG. 6 is a bottom view of the switch of FIG. 5;

FIG. 7 is a view of the side opposite that shown in FIG. 5;

FIG. 8 is a front view;

FIG. 9 is a palm supported finger operated switch of a further embodiment;

FIG. 10 is a bottom view of FIG. 9;

FIG. 11 is a view of the side opposite that shown in FIG. 9;

FIG. 12 is a front view of FIG. 9;

FIG. 13 is a perspective view of still another palm supported finger operated switch;

FIG. 14 is a bottom view of FIG. 13;

FIG. 15 is a view of the side opposite that shown in FIG. 13;

FIG. 16 is a front view; and

FIG. 17 is a cross-section of the finger operated portion taken along lines 7-7 of FIG. 13.

I claim:

The ornamental design for a palm supported finger operated switch, substantially as shown and described.
